(57) **CLAIM**

I claim the ornamental design for cell phone case with magnifying lens, as shown and described.

DESCRIPTION

FIG. 1 is a top, front, right side perspective view of the cell phone case with the magnifier lens in an extended position.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a top, front, right side perspective view of the cell phone case with the magnifier lens in a retracted position.

FIG. 9 is a front elevational view thereof.

FIG. 10 is a rear elevational view thereof.

FIG. 11 is a left side elevational view thereof; and,

FIG. 12 is a right side elevational view thereof. The top plan view thereof is identical to FIG. 6, the bottom plan view thereof is identical to FIG. 7.

The broken lines immediately adjacent the claimed surfaces represent boundaries of the claimed design. All other broken lines depict unclaimed environment. The broken lines form no part of the claimed design.
